COMBINED SEAT AND DESK

Henry O. Gervais, Deerfield, Fla., assignor to Henry Industries Inc., Wilkes-Barre, Pa., a corporation of New York

Filed Nov. 16, 1965, Ser. No. 88,124

Term of patent 14 years

(Cl. D33—14)

FIG. 1

FIG. 3

FIG. 2

FIG. 4

FIG. 1 is a front elevational view of a combined seat and desk showing my design.

FIG. 2 is a top plan view therof.

FIG. 3 is a rear view of FIG. 1.

FIG. 4 is a side elevational view thereof.

The caps shown on the ends of the legs in FIGURE 4 have been omitted from FIGURES 1 and 3 for convenience of illustration.

I claim:

The ornamental design for a combined seat and desk, substantially as shown and described.
